184,246

CONTAINER OPENER OR SIMILAR ARTICLE

Karl Usbeck, Marburg, Germany

Application October 18, 1957, Serial No. 48,154

Term of patent 7 years

(Cl. D44—29)

Fig. 1 is a front elevation of a container opener or similar article, showing my new design;

Fig. 2 is a side elevation;

Fig. 3 is a rear elevation;

Fig. 4 is a top plan view; and

Fig. 5 is a fragmentary elevational view along line 5—5 of Fig. 3.

I claim:

The ornamental design for a container opener or similar article, substantially as shown.
